M. KARP,

CONTAINER.

APPLICATION FILED OCT. 28, 1915.

1,261,032.

Patented Apr. 2, 1918.

Inventor

M. Karp.

By his Attorney

R. F. Bourne

UNITED STATES PATENT OFFICE.

MORRIS KARP, OF PASSAIC, NEW JERSEY, ASSIGNOR TO PASSAIC METAL WARE COMPANY, OF PASSAIC, NEW JERSEY, A CORPORATION OF NEW JERSEY.

CONTAINER.

1,261,032.

Specification of Letters Patent.

Patented Apr. 2, 1918.

Application filed October 28, 1915. Serial No. 58,403.

To all whom it may concern:

Be it known that I, MORRIS KARP, a citizen of the United States, and resident of Passaic, in the county of Passaic and State 5 of New Jersey, have invented certain new and useful Improvements in Containers, of which the following is a specification.

In my Letters Patent No. 1,103,674, granted July 14, 1914, I have disclosed a 10 container, such as an oil can, provided with a spout or nozzle adapted to be pushed within the can when not in use or for transportation, and to project from the can for use.

15 My present invention relates to improvements in the class of containers above referred to, and has for its object to simplify and reduce the cost of manufacturing and applying such spouts or nozzles to containers, whereby the number of parts are reduced.

20 My invention comprises novel details of improvement and combinations of parts that will be more fully hereinafter set forth 25 and then pointed out in the claims.

Reference is to be had to the accompanying drawings forming part hereof, wherein

Figure 1 is a partly sectional side view of 30 a container embodying my improvements showing the parts in position for use;

Fig. 2 is a sectional view of the upper portion of the container illustrating the parts in position for shipment;

Fig. 3 is a plan view of part of Fig. 2; 35 Fig. 4 is an exaggerated sectional detail of part of Fig. 1; and

Fig. 5 is a sectional detail of parts 8 and 11.

The numeral 1 in the accompanying 40 drawings indicates a container of any suitable construction, such as a tin can. The container is shown provided with a neck 2, shown having threads adapted to receive a correspondingly threaded closure or cap 3.

45 The neck 2 may be formed on or may be secured to the container as by solder or in any well known manner. Neck 2 is provided with a centrally disposed opening at 4 shown having an inturned flange at 5.

50 Neck 2 is also shown provided with an external projection 6 shown in the form of an annular rib adapted to receive a gasket or washer 7 within cap 3, to provide a close fit to prevent leakage of the contents of the 55 container with the parts in the position

shown in Fig. 2. At 8 is a hollow or tubular guide or support for an adjustable spout or nozzle 9, which is adapted to slide within said guide. The guide or support 2 extends within the container, and the outer 60 end of said guide is supported at an opening in the container, being shown supported at the opening 4 of neck 2, whereby spout or nozzle 9 may travel in and out through such opening. The guide or support 8 is 65 preferably made in tubular form to guide the annular flange 9^a on the inner end of spout 9. A washer or gasket 10 is shown carried by said spout and bears against said flange. The open outer end of guide or sup- 70 port 8 is provided with a collar 11. The collar 11 is shown in the form of a sleeve or tube receiving the open end of guide 8 and having a transverse wall 11^a extending over the open end of guide 8. Said wall is 75 shown provided with an opening at 12 in which spout 9 may slide. The collar 11 is to be secured fluid tight at the outer end of guide 8, and said collar is of such dimensions as to fit snugly in the opening 4 and 80 against flange 5 of neck 2, to prevent leakage at the joint therebetween. The collar 11 is adapted to fit snugly over one end of guide 8, and in order to afford a tight fit between said collar and guide, as well as 85 to afford a tight fit between said collar and flange 5 of neck 2, said collar and guide 8, after the collar has been placed upon the guide, may be compressed or rolled to cause the collar to taper inwardly in the direc- 90 tion of guide 8 from the wall 11^a, as illustrated more clearly in Fig. 4, and the flange 5 may be formed in an inwardly tapered manner to coact with the corresponding tapering surface of the collar. By com- 95 pressing the collar 11 upon guide 8, as in the manner stated, a tight fit may be effected between said parts without requiring them to be soldered together, although solder may be applied to said parts if desired. 100 The collar 11, secured upon the end of guide 8 in the manner stated, reinforces said guide in the manner of a ferrule, and affords a secure attachment of the guide to the container without danger of the guide becoming loosened. The outer surface of collar 11 is so located as not to interfere with the washer or gasket 7 when cap 3 is screwed on neck 2 to make a tight fit thereat, for 105 which purpose the upper surface of wall 11^a 110

of collar 11 may be substantially flush with or slightly below the surface of rib 6. Within guide or support 8 is a spring 13 shown bearing at one end against the flange of spout 9 and at its opposite end against the inturned abutment portion 8^a of said guide, the normal tendency of the spring being to press washer or gasket 10 against the laterally disposed wall 11^a of collar 11. 0 The inner end of guide 8 is shown open, and said guide may be provided with one or more openings 8^b near its outer end, to permit liquid to flow into said guide from the container. 15 Guide or support 8 and its collar 11 may be formed with the latter securely attached to one end of the former, and then the spout 9 having the washer or gasket 10 may be pushed into the opposite open end of the 20 guide, the spring inserted and the abutment portions 8^a of the guide bent against the corresponding end of the spring. The container having the opening 4 and flange 5 ready to receive the guide 8 may be charged 25 with the desired contents, and then the guide may be pushed into said opening to cause collar 11 to be fitted tightly in opening 4 against flange 5, the tapering surfaces between collar 11 and flange 5, when forced 30 firmly together, making a secure seam at the joint. The guide 8 thus is securely attached to the container or its neck with guide 8 extending into the container and supported by the neck, the spout extending outwardly, 35 the parts being assembled as illustrated in Fig. 1. The cap 3 may then be placed over the spout and the latter pushed inwardly with the cap, whereupon the latter may be screwed upon the neck for retaining the 40 parts, as illustrated in Fig. 2, for transportation and storage. When cap 3 is unscrewed from the neck the spout will be projected outwardly for use. The container may be 45 of a form having flexible walls to be squeezed to cause the outflow of the contents, or may be of any other desired form.

By means of my improvements I am enabled to reduce the cost of manufacture of this class of goods, eliminating some of the 50 parts heretofore utilized, and providing spouts and their guides ready to be pushed into place in the corresponding openings of the containers or their necks, without danger of leakage between the joints, and without 55 the liability of anyone unscrewing the guide and its spout from the container or can, thereby affording a degree of security

against the ready unauthorized refilling of the container.

Changes may be made in the details of 60 construction and arrangement of parts shown and described, as the same may be varied, within the scope of the appended claims, without departing from the spirit of the invention. 65

Having now described my invention what I claim is:—

1. The combination of a container having an opening, a guide having an exterior portion adapted to fit frictionally fluid-tight 70 against the inner wall of said opening to extend therefrom into the container, a spout slideable in the guide, said guide having an apertured wall at its outer end, a gasket to coat with said spout and wall to make a 75 tight fit when the spout is extended outwardly, a spring within the guide coacting with the spout and with the guide to normally press the spout outwardly, a cap, and means to removably attach the cap to the 80 container over the spout.

2. The combination of a container having an opening, a guide having a collar secured around its outer end adapted to fit fluid tight in said opening to support the guide extended into the container, said collar having a transverse apertured wall registering with the outer end of the guide, a spout adapted to slide and be retained within the guide and through said aperture, a gasket within the 90 guide to provide a close fit between the spout and said wall, a spring within the guide coacting with the spout and the guide to normally push said spout outwardly, a cap, and means to removably attach the cap 95 to the container over the spout to retain the latter within the guide.

3. The combination of a hollow guide, a collar fitted around the outer end of said guide and having a smooth outer wall to fit 100 frictionally in a support, an apertured wall extending across the end of said guide, a spout slideable in said aperture and limited in its outward movement by said wall, means to provide a fluid tight joint between the 105 spout and the wall, and means to retain the spout within the guide.

Signed at Passaic, in the county of Passaic, and State of New Jersey, October, A. D. 1915.

MORRIS KARP.
